UNITED STATES PATENT OFFICE.

SIMON LAKE, OF MILFORD, CONNECTICUT.

INTERNAL-COMBUSTION ENGINE.

1,096,780.

Specification of Letters Patent. Patented May 12, 1914.

Application filed April 27, 1912. Serial No. 893,701.

To all whom it may concern:

Be it known that I, SIMON LAKE, a citizen of the United States, residing at Milford, in the county of New Haven and State of Connecticut, have invented certain new and useful Improvements in Internal-Combustion Engines, of which the following is a specification.

The invention relates to certain improvements in internal combustion engines and particularly to that class of engines shown and described in Letters Patent granted to me March 3, 1908, No. 880,744 and Sept. 13, 1910, No. 970,063, and in my pending applications filed March 22, 1910, Serial No. 531,018; Nov. 21, 1910, Serial No. 593,562, and March 21, 1911, Serial Nos. 615,991, now Patent No. 1,067,258, dated July 15, 1913, and 615,992, now Patent No. 1,026,571, dated May 21, 1912.

The invention has for its object to provide a simple and highly efficient self-starting reversible double or single-acting heavy oil engine wherein a high pressure of air is obtained and utilized for the various operations of the engine; to provide an efficient fuel feeding device for spraying the fuel oil into the working cylinder in a thoroughly disintegrated condition thereby more thoroughly mixing the oil and air to produce a richer gas; to provide mechanism whereby to insure uniform quantities of oil and air being forced into the cylinder according to the load under which the engine is working; to provide mechanism to test the feeding of the oil to the cylinders; to provide a simple and efficient mechanism to control the admission of the oil and the air into the cylinder which also provides a reversing mechanism; to provide a construction whereby the heat of the cylinder is utilized to generate steam which is led into the cylinder for use as a power medium, and to provide a simple and peculiar construction of the base, crank-case and working cylinder whereby the crank-shaft, pistons and other internal working parts of the engine may be readily inspected and removed without necessitating the entire dismantling of the engine. These and other features germane thereto constitute the invention, as will be herein-after described and then pointed out in the claims.

In the accompanying drawings illustrating the invention, in the several figures of which like parts are similarly designated,

Figure 1 is a front elevation of the engine. Fig. 2 is an elevation of one end, the crank-shaft and part of the base and crank-case being shown in section. Fig. 3 is an elevation of the opposite end of the engine. Fig. 4 is a vertical longitudinal section, one of the power cylinders being shown in elevation. Fig. 5 is a transverse section drawn on the line 5—5 of Fig. 4. Fig. 6 is a transverse section drawn on the line 6—6 of Fig. 4. Fig. 7 is a plan view. Fig. 8 is a horizontal section on a larger scale drawn on the irregular line 8—8 of Fig. 4, the piston in the cylinder to the right being shown in plan. Fig. 9 is a horizontal section drawn on the line 9—9 of Fig. 10. Fig. 10 is a vertical section drawn through the upper end of one of the power cylinders and the piston working therein, the piston being shown in its extreme upper position. Fig. 11 is a horizontal section on a larger scale drawn on the line 11—11 of Fig. 4. Fig. 12 is a detail vertical section drawn on the line 12—12 of Fig. 11. Fig. 13 is a detail vertical section drawn on the line 13—13 of Fig. 11. Fig. 14 is a detail sectional plan view illustrating one of the worm wheels for operating the stuffing boxes surrounding the connecting rods connecting the power cylinders with the low compression air cylinders for supplying scavenging air to the power cylinders. Fig. 15 is a detail sectional plan view drawn on a larger scale on the line 15—15 of Fig. 1, illustrating the oil feeding pump and its connections. Fig. 16 is a transverse section on a larger scale drawn on the line 16—16 of Fig. 15. Fig. 17 is a sectional plan view of one pair of the fuel pumps. Fig. 18 is a vertical longitudinal section on a larger scale drawn through the sight feeding device, that is interposed in the supply pipe leading to the fuel pumps and by which the functioning of the pumps may be tested. Fig. 19 is a transverse section drawn on the line 19—19 of Fig. 18. Fig. 20 is a sectional elevation of the reciprocating shaft carrying the cams for operating the fuel and air valves leading to the power cylinders, illustrating one set of said valves and their co-acting mechanisms. Fig. 21 is a detail sectional plan view drawn on the line 21—21 of Fig. 20. Fig. 22 is a perspective view of one set of the cams for operating the fuel valves, and Fig. 23 is a perspective view of one set of the cams for operating the air valves. Fig.

23^a is a diagrammatic edge view of one of the air valve operating cams illustrating the contacting surface for operating the air valves to admit steam into the upper ends 5 of the power cylinders. Fig. 24 is a perspective view illustrating an arrangement for simultaneously operating all of the tripping pins which co-act with the fuel valve operating mechanisms. Fig. 25 is a vertical 10 longitudinal section on an enlarged scale drawn through one of the fuel valves. Fig. 26 is a detail section drawn on a larger scale on the line 26—26 of Fig. 25. Fig. 27 is a sectional elevation of the outer end of 15 said valve. Fig. 28 is an enlarged vertical section drawn through one of the air valves. Figs. 29, 30, 31, 32, and 33 are diagrammatic views illustrating the various positions of the cams for operating the fuel and 20 air valves; Fig. 29 showing the position of the cams when the engine is at rest; Fig. 30 illustrates their position for operating only the air valves when starting the engine; Fig. 31 illustrates their position 25 for operating one fuel valve and one air valve whereby to admit the fuel oil at one end of the cylinders and the air at the opposite ends; Fig. 32 illustrates their position when fuel oil only is admitted; and Fig. 33 30 illustrates their position when fuel oil and steam are admitted. Fig. 34 is a face view of the controlling lever and its connection to the reciprocating shaft for controlling the various positions of the valve operating 35 cams. Fig. 35 is a chart illustrating the various positions of the cams. Fig. 36 is a diagram of the card of the pistons when the engine is operating under air and fuel oil. Fig. 37 is a diagram of the card of the 40 piston when the engine is operating under fuel oil and steam. Fig. 38 is a vertical longitudinal section of the fuel feeding pump, illustrating a mechanism for automatically controlling the admission of the 45 fuel oil from the pump to the valves when starting the engine. Fig. 39 is a vertical section drawn on the line 39—39 of Fig. 38. Fig. 40 is a sectional plan of the pump.

The engine as shown, is of the vertical 50 type and is preferably built of two or more cylinders and while I have shown it constructed with two cylinders, I desire it understood that the same principle may be carried out with one cylinder or with a 55 multiplicity of cylinders according to the work for which the engine is designed. I have also shown it of the double-acting type, but it is obvious that the same principle may be carried out in a single-acting engine.

60 As illustrated, 1 designates the bed-plate or base of suitable design having water circulating chambers for keeping the bearings cool. From the bed-plate or base extend columns 2 upon the upper ends of which are 65 mounted the power cylinders 3 which rest

upon washers 4 supported upon suitable wedge-shape keys 4' held in slots formed in the columns, the cylinders being held firmly upon their seats by nuts 5 that are threaded upon the upper ends of the columns and serve to securely tie the whole engine together. The upper ends of the cylinders are formed with lugs 3' through which the columns pass as shown. Each cylinder is preferably constructed of an intermediate section 6, and an upper and lower section 7 and 8, respectively, the latter sections forming the heads of the cylinders and having double walls to provide water jackets in the usual manner. The central or intermediate sections 6 are formed with inner walls 9 that snugly fit against the inner ends of the end sections 7 and 8, and are provided with pluralities of centrally disposed air inlet ports 10 that extend entirely around the walls, and with outer walls 11 that extend in diverging directions from the upper and lower edges of the ports 10 past the upper and lower edges of the inner walls and terminate in flat flanges which rest upon annular shoulders 12 formed upon the outer walls of the end sections 7 and 8 of the cylinders, thereby providing, with said end sections 7 and 8, annular passageways 13 which are thrown into communication with the interior of the cylinders through ports 14 and provide exhaust passages for the escape of the products of combustion from the cylinders. The outer walls 11 terminate at one side of the cylinders in discharge mouths 15, to which may be connected manifolds 15' which in turn are connected by pipes (not shown) for conveying the exhaust gases to any desired place. The intermediate sections 6 may be water-jacketed if desired and preferably will be so constructed in large type of engines.

Working in each cylinder is a power piston 16, each of which has its ends provided with substantially funnel-shape sections 17 the base portions of which are spaced some distance from the ends of the cylinders so as to provide spaces or recesses 18 between the sections 17 and the ends of the cylinder, which spaces are designed to register with the air inlet ports of the cylinder when the piston reaches the end of each stroke thereby permitting the inlet of scavenging air to said cylinder to clean the same of the products of combustion at each stroke of the piston. As shown (Figs. 4 and 5) the discharge mouth of each section 17 extends some distance into its cylinder past the exhaust ports 14 and thus serves to carry the incoming scavenging air to a high point in the cylinder before actually entering the same and will thus, owing to its velocity, enter the cylinder in column formation and shoot upwardly or downwardly, as the case may be, and be directed against the ends

of the cylinder from which the air will be deflected and directed backwardly toward the end of the piston along the side walls of the cylinder to finally escape through the 5 exhaust ports 14, thus thoroughly cleansing the cylinders of all products of combustion resulting from the previous explosions. I have found from actual practice that the above described method of shooting a solid 10 column of air through the center of the pistons and through the center of the cylinders affords a more thorough scavenging of the exhaust gases which are driven out ahead of the air injected into the cylinders. The 15 ends of the cylinders are formed with recesses 19 to receive the mouth portions of the sections 17 when the pistons reach the extreme ends of their strokes, and the upper section 7 of each cylinder is provided with 20 a depending hollow steam pocket 20 which extends down into the mouth of the section 17 of its co-acting piston when the latter reaches the end of its upper stroke, thereby taking up the space within and reducing the 25 capacity of the cylinders to allow for a high compression of the air within the cylinder to ignite the fuel injected therein. These pockets 20 also serve as steam domes and communicate with the upper ends of the 30 water jackets of their respective cylinders through ports 20', whereby the steam generated in said jackets may escape into the domes and wherein the steam is superheated before being injected into the power cylinders 3 as will be more fully described hereinafter.

The lower ends of the sections 8 of the cylinders 3 are formed with hollow rectangular casings 21 from the lower sides of 40 which and tandem with their respective cylinders are double-acting air compression cylinders 22, each having a piston 23 working therein which is connected to its co-acting power piston 16 by a connecting rod 24 and 45 by a connecting rod 24' to a crank 25 of the main crank-shaft 26 that is journaled in the bed-plate or base 1 of the engine. The connecting rods 24 extend through the mouth portions 17 at the lower ends of the piston 50 and operate through stuffing-boxes 27 in the casings 21, the glands 28 of the boxes being threaded into threaded sockets of the stuffing-boxes and have their threaded sections formed with worm teeth 29 that are engaged 55 by worms 30 carried at the inner ends of shafts 31 which are journaled in the said casings 21 and have their outer ends provided with hand wheels 32 by which the shafts are rotated. It will be evident that 60 by rotating the shafts, the glands will be revolved in one direction or the other to either set up the packings or to entirely remove the glands when new packing is to be inserted.

Surrounding the power cylinders from the

upper ends of the intermediate sections 6 to the lower ends of the rectangular casings 21 is a housing 33 which is constructed of plating and connected together and to the cylinders so as to provide an air receiving 70 chamber that entirely surrounds the cylinders and into which air is forced from the upper ends of the air compression cylinders 22 from which it escapes into the power cylinders to scavenge the latter when the exhaust ports are uncovered. 34 designates inwardly opening valves controlling the admission of atmospheric air into the upper ends of the air compression cylinders, and 35 designates outwardly opening valves controlling the communication between the said upper ends of the air compression cylinders and the air receiving chambers.

Surrounding the air compression cylinders 22 and connected to the bed-plate or 85 base of the engine, is a housing 36 which is connected to said cylinders and the base airtight so as to provide an air compression chamber in the base of the engine. This housing is made in two sections 37 and 38 90 which are divided on a line with the longitudinal axis of the main crank-shaft of the engine, the sections being slidably mounted on the columns 2 so that they may be elevated as shown in dotted lines, Fig. 5, when 95 it is desired to get at the crank-shaft or to remove any of the journals, thus avoiding the taking apart of the entire engine or the uncoupling of the cylinders as is the case with the construction of engines now in use. 100 Each section of the housing is constructed with ends 40 and with a centrally arranged division plate 40' the lower ends of which are forced to snugly fit upon the upper sections 39 of the main bearings, and when securely fastened in place the housing divides the base into two air compression compartments, which are thrown into communication with the upper ends of the air compression cylinders 22 by air passages or channels 42, 110 Fig. 5, which communicate with the said upper ends of the cylinders through ports 41 formed in the sides of the cylinders thus as the pistons 23 are moved downwardly in their cylinders, the air that has been previously drawn into the base through the inwardly opening valves 44 carried by the section 38 of the housing, will be compressed in the base from which it escapes into the upper ends of the cylinders 22 the moment 120 the ports 41 are uncovered, so that on the next upstroke of the pistons 23 the air will be forced into the air receiving chambers surrounding the power cylinders 6. It will of course be understood that when the pistons 23 reach the ends of their down stroke, the valves 34 will be automatically closed which will prevent the escape of the air from the upper ends of the cylinders into the atmosphere. As shown, the section 38 of 130

the housing is of a greater height than the section 37 thereby providing for the passages or channels 42, and surrounding the semicircular openings at the tops of the sections of the housing the said tops are formed with recesses to receive glands or packing rings 43 to make the joints around the cylinders airtight.

At the forward end of the engine the sections 37 and 38 of the housing are formed with extensions 37' and 38' which are mounted air-tight upon an extension 45 of the base 1 so as to provide a compression chamber 46 similar to the compression chambers 15 below the cylinders 22 and carried by the extensions is a three stage air compressor which is employed for furnishing the compressed air used in the various operations of the engine. The compressor consists of 20 a two stage low compression cylinder 48 which is open at its lower end to the chamber 46 and two high-pressure cylinders 49. Working in the cylinder 48 is a compressing piston 50 which is connected by a connecting rod 51 with a counterbalanced crank-arm 52 carried at the forward end of the main crank-shaft of the engine. The head of the cylinder 40 is provided with an air inlet opening 47 that is controlled by an inwardly opening suction valve 53, and a discharge port 54 that is controlled by an outwardly opening valve 55. The port 54 is connected by a pipe 56 with a receiving tank 57 which is connected at its lower end by a 30 branch pipe 58 with the two high compression cylinders 49, in each of which operate plunger pistons 49' that are carried by the piston 50. The branches 58 of the pipe have check valves to prevent back pressure into 35 the receiving tank 57 as will be readily understood. The high compression cylinders 49 are also connected by pipes 60 with a branch pipe 61 that extends to a high pressure receiving tank or reservoir 62, the pipes 40 being also provided with back pressure valves to prevent back flow of the air into the cylinders 49 from the tank 62. The compression chamber 46 communicates with the upper end of the cylinder 48 through 45 passages 63 (Figs. 4 and 6) and ports 64 that open into the cylinder, which ports are controlled by the piston 50. Air is admitted to the chamber 46 through an opening 65 formed in the front wall 37' of the housing 50 and is controlled by an inwardly opening valve 66. In the operation of the compressor, as the piston 50 is drawn downwardly, air will be drawn into the upper end of the cylinder 48 through the opening 47, the 55 valve 53 being opened against the tension of its spring by the vacuum created in the cylinder, and is held in such position until the piston reaches the end of its stroke when the valve will be automatically seated. At 60 the end of its down stroke, the piston will

uncover the ports 64, which allow the air that has been compressed in the chamber 46 on the down stroke of the piston to escape into the upper end of the cylinder 48, raising the pressure therein above atmospheric pressure, then on the next up or return stroke of the piston the air thus trapped in the upper end of the cylinder will be further compressed and forced into the first receiving tank 57. Now as the piston 50 is forced up in its cylinder 48 the plunger pistons 49' will also be drawn upwardly in their cylinders 49, which allows the air in the receiving tank 57 to escape into the cylinders 49; then on the succeeding down stroke of the pistons 49' the air thus drawn into the high compression cylinders 49 will be further compressed and forced into the high pressure receiving tank 62, from which it is drawn for use in the engine as will be hereinafter described. It may be stated here that the compression cylinders are provided with water jackets to keep the parts relatively cool and that the receivers act to keep the air cool and are provided with caps over the ends of the inlet and exhaust pipes to deflect the course of the air and thus separate the moisture from the air and prevent it being carried off into the engine through the pipes connecting said tank with the engine. 95

67 designates air inlet ports extending into the upper and lower ends of the power cylinders and adjacent to each air inlet port is a fuel port or passage 68, the said ports being thus arranged in pairs are extended through lugs or extensions formed integral with the end sections of the power cylinders, which extensions form connections for the air valves 69 and the fuel valves 70 which control the admission of the air and the fuel through the respective ports to the cylinders. 100

As shown in Fig. 28, the casings of the air valves 69 are constructed with horizontal sections 71 which communicate with the air inlet ports 67 of the cylinders and with vertical sections 72 to each of which is connected one end of an air supply pipe 73 extending from a common pipe 74 that extends 110 from the high pressure air tank 62. In the vertical portions 72 of the valve casings are valves 75 which control the passage of the air to the cylinders, the stems 76 of the valves are extended through the casings and 115 through stuffing boxes 77 formed therein and are engaged by push rods 79 to open the valves as will be hereinafter described. The valves 75 are held to their seats by springs 80 which are carried in bonnets 80' screwed into the outer ends of the vertical sections of the casings. The inner ends of the horizontal sections of the casings are fitted with valve casings 81 which carry spring seated 120 back pressure valves 81' which serve to pre- 125

vent the products of combustion and the force of the explosions in the cylinders from entering the valve casings and the air supply pipes connected thereto, thereby positively cutting off the communication between the ends of the cylinders and the valve casings, when the fuel is ignited in the cylinders. A valve 83 is arranged in the pipe 74 to control the admission of the air to the several pipes 73. The fuel valves 70, (Fig. 25), are each substantially alike and each is constructed of a casing 85 which is provided with a longitudinal bore of different diameters as indicated at 66, 67 and 68, in the inner section 66 of which is screwed a plug 89 whose inner end is formed with a cone-shape valve seat. From the base of the cone is extended a plurality of fuel passages 90 that extend through the plug in converging directions so as to discharge direct into the small fuel passages 68 of the cylinders. In the section 87 of the bore is screwed a gland sleeve 91 in which is slidably held the stem of a tubular valve 93 whose outer end snugly fits into the inner end of the bore 66 and has its extreme end ground to provide a valve seat to snugly fit the intermediate section of the cone end of the plug 89. The outer end of the stem of the valve is formed with a head between which, and a plug 94 screwed into the outer end of the section 68 of the bore, is interposed an expansion spring 95 which firmly holds the outer end of the valve 93 to its seat. In the bore of the tubular valve 93 is fitted a tubular valve 96 having a threaded section which is screwed into the outer threaded end of the valve 93 thus securely holding the said valve 96 to a fixed position relative to the valve 93 to cause it to move in unison therewith. The inner end of the valve 96 is reduced as at 97 and loosely fits within the reduced bore 96' at the inner end of the valve 93 so as to provide an angular fuel outlet or nozzle leading from the stem of the valve 96 as later explained. The extreme inner end of the valve 96 is ground to provide a valve seat which snugly fits the apex of the plug 89, and the said inner end is provided with a central air passage or nozzle which is controlled by a needle valve 98 whose stem is extended entirely through the valve 96 and through a stuffing box at the outer end thereof, and is provided with a threaded section 99 which operates in a threaded surface of the bore of the valve 96, whereby the valve 98 may be adjusted to regulate the discharge of the air through the passage at the end of the valve 96. The inner end of the stem is rectangular in cross-section (Fig. 26) to provide longitudinal passages in the valve and is provided along its edges throughout its length with notches so as to throw said passage in the valve into communication with

each other. The outer end of the shank is provided with a milled head to facilitate the rotation of the said stem in adjusting the valve to or away from its seat.

On the outer end of the stem of the valve 70, 96 is threaded a band 100 having oppositely disposed lugs which fit in slots formed in the forked end 101 of an elbow lever 102 that is pivoted intermediate its ends to an arm 103 extending from the casing 85. The levers are designed for engagement by push rods 104, also hereinafter fully described, whereby the ends of the sliding valves 93 and 96 may be withdrawn from their seats to allow the fuel oil and air to enter the cylinders.

Each valve casing 85 is formed with oppositely disposed hollow extensions 104 and 105 in which are held glass cylinders 106 that are held in place by caps 107 and 108, respectively, which are screwed into the outer ends of the said extensions. The cylinder in the extension 104 is provided with a central bore which communicates at one end with a fuel inlet passage 107' in the cap 107, and at its opposite end with a port 109 in the valve casing, which port 109 communicates with a port 110 in the gland 91 that is arranged opposite a port 111 in the valve stem 93, which in turn communicates with an annular passage 112 formed in the valve stem 93, from which extends a longitudinal slot 113 that extends to the outer end of the said valve. A fuel supply pipe 114 is screwed into the passage 107' of the cap 107, and a ball valve 115 is arranged in the lower glass cylinder 106 and seats against the cap 107, and thus traps the oil forced into the casing.

The glass cylinder 106 in the extension 105 has a central bore or passage which communicates at its upper end with a passage 108' of the cap 108, and at its lower end with a port 116 arranged in the casing 85 at the base of the extension 105, said port 116 being disposed opposite a port 117 in the gland sleeve 91 which latter port communicates with a port 118 in the valve stem 93 that in turn communicates with the annular passage 112 of the valve 96.

119 designates an air inlet port in the outer end of the casing 85 which communicates with the bore 68 between the inner end of the valve stem 93 and the inner end of the cap or plug 94; and 120 designates an air port in the stem of the valve 96 that leads from the said bore 68 into the bore of the stem of the valve 96. Air under pressure is supplied to the valve through a pipe 121 which extends from the common supply pipe 74 and has its end connected to the port 119, and extending from the pipe 121 is a branch pipe 122 whose outer end is connected to the cap 106 to supply air to the passage 108'. The extensions 104 and 105 are 100

provided with eight openings 123 whereby the action of the oil passing through the glass cylinders may be observed and the proper feeding of the oil to the cylinders 5 thus ascertained.

The foregoing description, it will be understood, applies to all of the fuel feeding valves and in order to avoid confusion I 10 have applied only the general reference characters to the several valves throughout the assembled figures of the drawings, and invite attention to the detail figures for the detail of construction.

Briefly, the operation of the fuel valves is 15 as follows: Air is constantly supplied to the valve under a pressure of about 900 lbs., and the oil is forced (pumped) in measured quantities at a pressure of about 1000 lbs., and in such quantities when the engine 20 is working under a heavy load to completely fill the channel in the lower glass cylinder 106, the ports leading therefrom, the channels in the stem of the valve 96 the ports leading therefrom and up into the upper 25 glass cylinder to about half its height. Now when the fuel is to be injected into the power cylinder the valves 93 and 96 will be drawn from their seats or "cracked" when owing to the air pressure on the top of 30 the oil in the upper glass cylinder, the oil will be forced out through the contracted nozzle or mouth 96' of the valve 96 against the inner cone end of the plug 89 by which it is deflected, in what might be termed a 35 funnel-shape column, toward the base of the cone and is finally forced out through the channels 90 in the plug and into the cylinder. Simultaneously with the opening or cracking of the valve 93 the valve 96 will 40 also be "cracked" to allow the air in the stem of the valve 96 to escape through the end of the valve and striking against the apex of the cone will be deflected in all directions into and against the column of oil 45 which will break up the oil and spray it into the cylinder in a thoroughly disintegrated condition and wherein the vapor will be instantly ignited to drive the piston on its power stroke. It will be evident from the 50 construction shown and described, that the oil will be forced from the mouth 96' in a hollow funnel-shape column and that the air escaping through the central air outlet of the valve 96 will be directed into the hollow column of oil and owing to its expansion 55 will spread out and strike the oil with great force and thus serve both to break it up and to assist the air pressure on top of the oil to force the oil into the cylinder. I 60 have found from experiments that by injecting highly compressed air into a hollow column of oil as the latter is forced from the valve that a very fine light vapor will result and completely fill the atmosphere and that 65 a sheet of paper held only a short distance

from the nozzle of the valve will not even be damped, thus proving that the oil is thoroughly broken up and vaporized and spread out in all directions. Each charge of oil that is injected into the valve casing 70 will lift the ball valve 115 in the lower glass cylinder 106 around which it passes up into the channels afore described and the moment the pressure back of the valve ceases, the valve will drop back on its seat and thus 75 trap the oil in the casing, and as the ball will rise and fall with each charge of oil injected into the valve casing it provides an arrangement whereby one is enabled to detect the imperfect feeding of the oil to 80 the cylinder.

Oil is forced into the valve casings through the pipes 114, by means of pumps 124 which are arranged in a group and carried by a platform or shelf 125 extending 85 from the front of the engine. The pumps 124 are arranged in pairs which are coupled together as shown in Fig. 15, and each pair is constructed with a base 126 in which are arranged two parallel piston cylinders 127 90 in each of which operates a piston 128, all of these pistons being carried by a reciprocating block or head 129 slidingly held on guides 129' which also serve to connect the base portions of the two pairs of pumps. The piston 95 block or head 129 is connected to one end of a connecting rod 130 pivotally connected near its opposite end to a sliding block 131 which is retained in an oscillating arm 131' pivotally connected at one end to a bracket 100 132 extending from the platform 125 and which arm has its opposite end provided with a downwardly extending lug 133 held in a short slot 134 arranged in the inner end of a reciprocating plate 135 which is slidingly retained upon and at the outer end of the platform 125. In the outer end of the plate 135 is a crank arm slot 136 in which operates a crank 137 of an operating shaft 137 journaled in brackets 138 extending 110 from the engine and having its lower end provided with a worm wheel 139 meshing with a worm wheel 140 which in turn meshes with a drive worm wheel 141 carried by the main crank-shaft of the engine. By thus 115 connecting the piston block of the pumps with the drive shaft 137 it will be apparent that as the said shaft is rotated the block will be moved back and forth to first draw the oil into the pump cylinders and then 120 force it therefrom through the pipes leading to the valve casings 85. Oil is fed to the pump cylinders through pipes 142 connected to valve cylinders or casings 143 screwed into the pump casings, and the pipes are 125 connected at their opposite ends with ports or passages 144 formed in a casing 144' and which lead into a common passage 145 to which a supply pipe 146 extending from a supply tank (not shown) is connected. The 130

ports or passages are controlled by plug cocks 117 from which also lead by-passes 148 that extend upwardly through the top of the casing and from which extend glass tubes 149 whose upper ends are provided with valve casings having inwardly opening vent valves 150 as shown in Fig. 18. Each plug cock is provided with an operating handle *x*.

10 By the above described arrangement the passage of the oil from the supply tank to the pumps may be ascertained and the proper working of the pumps determined. Ordinarily the passages through the plug-cocks are adjusted as shown at the left of Fig. 18, so that the oil may flow direct from the common passage 145 to the pipes leading to the pumps and the glass tubes are kept partly filled. Now, when it is desired 20 to test the working of any particular pump the handle of the plug-cock controlling the passage thereto is thrown over so that the passage through the cock will be caused to register with the port 114 leading to the 25 particular pump, and the port 148 leading into the glass tube communicating with the particular pump cylinder as shown at the left of Fig. 18, then as the pump is operated a certain quantity of the oil will be 30 withdrawn from the tube at each stroke of the pump piston instead of from the common passage 145, thus enabling the operator to ascertain the working or efficiency of any pump without stopping the engine. 35 It is obvious that by the above described arrangement all of the pumps may be tested as rapidly as the plug-cocks can be adjusted. It may also be stated that the glass tubes are large enough to hold a number of 40 charges of oil so that successive operations of the pumps may be watched without again operating the cocks to refill the tubes. When the tubes are filled, the valves 150 are unsated by pressing down upon the 45 valve stems which normally project above the tops of the tubes, thus venting the tubes so that the oil may readily flow therein.

Communicating with each cylinder of the fuel pumps is an oil outlet port 151 to each 50 of which is connected one of the pipes 114 for conveying the fuel to the valves 70. An outwardly opening check valve 152 is arranged in each outlet port 151 to prevent the return of the oil into the pump cylinders 55 on the return stroke of the pistons.

In order to regulate the quantities of fuel injected into the cylinders as the load of the engine varies, I provide the shaft 157 with a governor 153 which may be of any suitable design, and to the vertical movable clutch ring 154 of the governor is operatively connected the outer end of a lever 155 carried at one end of a short shaft 155' journaled in a bracket extending from the 60 engine frame, and to the opposite end of

the shaft is connected a downwardly extending lever arm 156 whose free end is connected by a universal joint to a link 157 which is in turn connected to the extreme outer end of the connecting rod 130, so that 70 as the speed of the engine increases and the movable clutch ring 154 is elevated, the lever 155 through its connections will move the sliding block 131 toward the inner or pivotal end of the oscillating arm 131' thus 75 shortening the stroke of the fuel pump pistons and consequently decreasing the supply of oil pumped into the valve casings, whereas on the other hand should the engine slow down the sliding block will be 80 moved toward the outer end of the arm 131' to thus increase the stroke of the pistons to force a greater quantity of oil into the valve casings.

The operation of the engine is controlled 85 by a common shaft which is designated as a whole by the reference character 160, Fig. 20. This shaft is formed of a tubular section 161 mounted in bearings 162 extending from the front plate of the housing surrounding the power cylinders, and revolvably held in the tubular section 161 is a shaft 163 provided at its outer end with a plurality of ribs 164 which are held in grooves arranged in the inner end of an arm 165 provided at its outer end with a crank slot 166 in which operates a crank 167 formed in the upper end of the vertical shaft 157. A cap 168 is fitted over the ribs 90 of the shaft to hold the latter in position 100 in the arm. Adjacent to its outer end the shaft 163 is provided with a series of spiral worm threads 169 which operates in correspondingly arranged recesses formed in the outer end of the tubular section 161 whereby when the shaft 163 is reciprocated the tubular shaft section will be caused to move in unison therewith. The inner end of the tubular shaft 161 is provided with a rack pinion 190 whose outer face is formed with 105 a series of sockets engaged by a locking pin 191 (Fig. 20), carried on the inner face of a hand wheel 192 mounted on the inner end of the shaft 163 which locks the two shafts together to cause them to be rotated together and which permits of a longitudinal adjustment of the tubular shaft 161 for the purpose of adjusting the operating cams carried thereby, as will be hereinafter described. The rotative movement of the 110 shaft 160 is controlled by an operating lever 193 that is mounted in a bracket 194 extending from the housing 36, said shaft having a segmental rack section 195 engaging the pinion 196 whereby the operation of the 115 lever will rotate the shaft 160 to control the operation of the engine. The lever is provided with any suitable form of locking mechanism 198 for holding the lever in its 120 adjusted position.

Upon the shaft section 163 is mounted a series of push cams 197, 198, 199, and 200, which are designed for engagement with rocking arms 201 and 201' pivoted to brackets extending from the face plate of the housing 33. The arms are provided with contacts 202 that engage disks 203 carried at the inner ends of vertically movable hollow rods 204 slidingly retained in brackets 205, also extending from the face plate of the housing, said hollow rods carry the push pins 79 and 104, respectively, whose outer ends operate in bracket arms 207 extending from the brackets 205 and have their extreme ends arranged adjacent to the valve stems 76 of the air valves 69 and to the levers 102 of the fuel valves respectively, whereby as the shaft 160 is reciprocated the cam blocks, presently explained, will engage and rock the arms 201 and 201' to operate their respective valves to admit air and fuel oil into the cylinders. The push rods 206 are provided with shoulders between which and the brackets 207 are interposed springs 25 which normally hold the disks into contact with the contacts 202 of the rocking arms and which also serve to hold the outer ends of the push rods away from the valve operating connections. The contacts of the disks 30 201 for operating the air valves are preferably formed integral with their disks, but those of the fuel valve operating disks 201' are preferably pawls which are pivoted between ears extending from the sides of said 35 arms and are provided with outwardly extending portions that are adapted for engagement with adjustable contacting pins 210, carried by the brackets 205 so that as the arms 201' are rocked in one direction or 40 the other the pins 210 will engage one or the other of the pawls after the arm has been rocked a certain distance and trip it from engagement with its disk, thereby releasing the valve to cut off the supply of fuel to the 45 cylinders. It is obvious that by adjusting the pins 210, the quantity of fuel admitted to the cylinders may be easily regulated. The pins 210 are threaded for a portion of their length and have their outer ends provided with milled heads to facilitate their adjustment, and in order to adjust all of the pins simultaneously I may provide them with crank arms 211, as shown in Fig. 24, and connect the outer ends of the arms by 50 connecting rods 212 which in turn are connected by a rod 213' having a handle as shown. By this arrangement, it will be seen that by pushing the rod 213' in one direction or the other the pins 210 will be simultaneously adjusted up or down to either advance or retard the seating of the valves to increase or diminish the quantity of fuel and air supplied to the cylinders.

The lower ends of the rocking arms are 65 provided with roller contacts 213 and are

held in vertical position by flat springs 215 that are carried by their pintles and have their free ends held between ears extending from the front face of and at the inner ends of the arms.

As shown and described, the engine is double-acting, that is to say, each stroke of the piston is a power stroke, similar to the operation of the steam engine, and is also shown and described as being operable either by air or air and fuel oil, as when starting the engine, or by fuel alone when the engine is under full power, and in consequence it is necessary to arrange an air valve and a fuel valve at each end of the power cylinders; this therefore necessitates a peculiar construction of the push cams and their mounting whereby they may be adjusted to permit of the operation of the engine under the various operative mediums and in reverse directions. In Figs. 22 and 23 I illustrate one set of push cams that are employed for each cylinder of the engine and in the description to follow will assume that the engine is constructed with only one power cylinder and therefore we will consider only the one set of cams. As shown in Fig. 22, the push cam 197 is provided with a single contacting surface 197', that of cam 198 with a double contacting face 198', those of cams 199 and 200 with double faces 199' and 200' respectively, the faces of the latter cams being separated by intervening spaces 300. These cams are so arranged on the reciprocating shaft 160 relative to one another that when adjusted to certain positions for the admission of the different power mediums to the cylinders that they will alternately engage the swinging arms 201 and 201' as the shaft 160 is reciprocated. The locations of the cams and their operation will be best understood by reference to Figs. 29 to 34, both inclusive, and to the chart Fig. 35, and the following description.

As shown in Fig. 34, the controlling lever 193 is set so as to adjust the cams out of alignment with the rocking arms, (Fig. 29), 201 and 201' so that the engine will be at rest. Now should it be desired to run the engine ahead, the lever is brought over to its first position which, through the medium of the segmental rack section of the lever, will rotate the shaft 160 to adjust the cams to the position shown in Fig. 30 which adjusts the cams 199 and 200 so that their contacting surfaces will alternately engage and rock the arms 201 and 201' at the upper and lower ends of the cylinder to alternately open the air valves at said ends, which admits the compressed air from the receiving tank 62 to the power cylinder to alternately drive the power piston on its down and up strokes. After the engine has thus been started and has attained sufficient speed to compress the air in the cylinder to a point

wherein it will ignite the fuel when the latter is injected into the cylinder, the lever 193 is thrown to its second position to adjust the cams to the position shown in Fig. 5 31 to throw one fuel valve operating cam (the double face cam 198) into position to engage its rocking arm 201' on one direction of the movement of the shaft 160 to admit fuel oil into the upper end of the cylinder 10 which leaves only one air valve operating cam (cam 200) in position for engagement with its rocking arm 201 to admit a charge of compressed air into the opposite end of the cylinder on the reverse movement of the 15 shaft 160. Thus it will be seen that the engine will be running on alternate charges of compressed air and fuel oil. Now, when the lever is thrown to its third position the cams will be adjusted to the position shown 20 in Fig. 32, in which position both of the air valve operating cams 199 and 200 will be thrown out of operative position and both fuel valve operating cams 197 and 198 thrown into position, thus alternately operating the fuel oil valves at the upper and lower ends of the cylinder on each stroke of the shaft 160 to admit fuel oil to both ends of the cylinder. It will thus be seen that the operation is exceedingly simple and requires but the one lever to control the various 30 adjustments. It will be understood that in reversing the direction of movement of the engine it is only necessary to throw the lever in the opposite direction to that described in reference to driving the engine ahead.

In practice the power shaft 26 is so set with relation to the reciprocating shaft 160, that when the crank of the main shaft is at 40 the top of its rotating position, or on a "dead center" the shaft 160 is at one half of its stroke, or at that portion of its stroke that the fuel valve operating cam 197 is just in contact with its rocking arm when the 45 said shaft is being moved in the direction indicated by the arrow in Fig. 20, so that the remaining movement of the shaft will open the fuel valve to admit the fuel to the cylinder, and as it is obvious that the fuel 50 valve will be held open during this movement which corresponds to a 90 degree movement of the main shaft, the high pressure air will continue to flow into the cylinder and thus unnecessarily waste the air; 55 therefore I have provided the said valve operating rocking arms 201' with the pawls and their contacting points so that the length of time the valves are to remain open may be regulated to seat the valves and cut 60 off the air supply at any point on the cycle of the piston to admit greater or less quantities of fuel and air into the cylinders according to the load under which the engine 65 is operating, it being obvious that by adjusting the contact or tripping points, the valves

may be regulated to seat themselves at the time desired.

In order that the cams may be adjusted to admit the fuel to the cylinder at various points of the stroke of the piston, which is necessary according to the grade of oil used, I provide the shaft 160 with the adjustable section 161 so that by rotating the hand wheel 192 of the shaft 163 the said shaft will be rotated and this shaft being held in a fixed support (the arm 165) the sleeve 161 and consequently the cams will be moved in one direction or the other to thus advance or retard their contact with their co-acting rocking arms at an earlier or later period in the movement of the shaft 160.

In order to prevent the flooding of the power cylinders when the engine is started under air alone, and to admit the fuel oil to one end of said cylinders only when the engine is operating under compressed air and fuel oil, I provide the fuel pumps with cylindrical bores 210' which traverse the pump cylinders adjacent to their inlet ends, and in each bore is arranged a cut-off slide 90 valve 211' each having a cylindrical oil passage 212' and an elongated oil passage 213'' that are designed to be moved into and out of register with the pump cylinders to thus cut-off or open up communication between 95 the pump cylinders and the supply pipes. When the engine is first started the slide-valves are adjusted to the position shown in Fig. 17, which acts to completely cut off the oil supply to the pumps, and when the oil is to be injected into one end of the power cylinder only as hereinbefore described, the slide valve is pulled outwardly until the slot 213'' registers with its adjacent cylinder then as the pump is operated the fuel oil 100 will be pumped into its valve casing, then upon a further outward movement of the valve the cylindrical passage 212' will be brought into register with its pump cylinder and oil is thus supplied to both cylinders of 105 the pump, the slotted passage 213'' permitting this second movement of the slide valve without cutting off the supply to the first pump cylinder. The outer ends of the slide valves are provided with upturned sections 110 to provide handles to facilitate their operation.

In Figs. 38, 39 and 40, I illustrate an arrangement for automatically cutting off and opening up the communication between the fuel pumps and their supply pipes whereby the supply of oil to the pumps is controlled by the control lever 193. In this construction I provide the pumps with bracket arms 214 in which are journaled the ends of a 120 rocking shaft 215' which is provided adjacent to its ends with downwardly extending crank arms 216 whose free ends are provided with pin slots in which operate stud pins carried by and at the inner ends of 125 130

the cut-off slide valves 211'. Intermediate the ends of the shaft 215' is arranged an inwardly extending crank arm 216' to which is connected the lower end of a vertically movable rod 217 which is mounted at its lower end in a bracket 218 extending upwardly from one of the pumps, and whose upper end is held in a guide bracket 218' extending from the face plate of the engine 10 and has its extreme end provided with a head in which is mounted a roller 219 that is adapted for engagement with a double three face cam 220 carried by the reciprocating shaft 160. A collar is arranged upon 15 the rod 217 between which and the lower bracket 218 is interposed a spring 221 for elevating said rod and correspondingly moving the sliding cut-off valve when the shaft is rotated to bring the different cam surfaces into opposite position with the roller. 20 A stop 222 is arranged on the rod 217 to limit the upward movement of said rod and which is so located as to hold the roller away from the cam 220 when the engine is 25 running under fuel oil alone. When the engine is at rest and when in operation under air alone as in position No. 2, the roller 219 will bear against the broad surface "a" of the cam which holds the cut-off valve in its 30 extreme inward position with both oil passages out of alignment with the pump cylinders, and when the shaft 160 is revolved so as to adjust the air and fuel valve operating cams to position No. 3 when oil is admitted 35 to only one end of the cylinder and air to its opposite end, one of the surfaces "b" will be brought opposite the roller 219, when the spring 221 will lift the rod and consequently move the cut-off valve over one position 40 which will throw one of the pump cylinders into communication with its oil supply pipe but holding the other cylinder out of communication with its pipe; then upon a further movement of the shaft 160 to 45 adjust the cams to position No. 4 the cut-off valve will be further adjusted to throw both cylinders of each pump into communication with their supply pipes.

223 designates a steam dome arranged at 50 the top of the power cylinders 3 which is connected by pipes 224 with the superheating steam drums or pockets 20 arranged in the upper heads of the power cylinders and from this dome is extended a pipe 225 which 55 connects with the air supply pipe 73' which extends to the air valves 69 at the upper ends of the cylinders. The pipe 225 is provided with a cut-off valve 226 and with a check valve 227 (Fig. 1) to control the admission of the steam from the dome 223 to the said air pipe. The air pipe 73' between its connection with the air valves at the upper end of the cylinder and the pipe 73' leading to the air valves at the lower ends 60 of the cylinders is provided with a check

valve 228 to prevent the steam in the dome from entering the pipes leading to the lower air valves in the event of the pressure in the steam dome exceeding that in said pipes and that of the air receiver 62.

The operation of one cylinder of the engine is as follows: Assuming that the engine is at rest, that there is a pressure of say 1000 lbs. of air on the high pressure receiving tank 62 and that the engine is to be run in the ahead direction, the operator first throws the controlling lever to the left as shown by the arrows in Fig. 34 to its first position which will bring the air valve operating cam into engagement with the air valve operating rocker arm at the upper end of the cylinder to first open the air valve at said upper end to drive the piston downwardly to rotate the power shaft in the direction of the arrow in Fig. 2; this operation it may be said here, being rendered possible owing to the setting of the cams on the shaft 160 in relation to the position of the power shaft, therefore when the operating lever is thrown over to rotate the shaft 160, the air cams will engage the rocker arm co-acting with the air valve at the upper end of the cylinder to admit air into the cylinder to thus drive the piston on its initial stroke. After the engine has made several revolutions on the air power and when it has attained sufficient speed to insure the proper compression in the main cylinder, the controlling lever is thrown to its second position to further rotate the shaft 160 to adjust the cams (Fig. 31) so that the fuel valve operating cam at the lower end of the cylinder will be moved into operative position but still leaving the one air valve operating cam at the opposite end in position to continue to operate upon the one air valve, thus driving the piston at one end of the cylinder on air and at the opposite end on fuel oil, then upon a further adjustment of the controlling lever the shaft 160 will be further rotated to throw both air valve operating cams out of and both fuel oil operating valve cams into position to co-act with their respective rocker arms as the shaft 160 is worked back and forth. During this operation, (and it may be stated also during the operation when the fuel oil is admitted only to one end of the cylinders), as the power piston is forced to the opposite end of its cylinder from the combustion of the fuel charges therein the low pressure air piston 23 will be operated in its cylinder and as it is moved upwardly air will be first drawn into the base of the engine, then on the next down stroke the air thus admitted to the base will be fully compressed in said base from which it escapes through the port 41 into the upper end of the air compression cylinder 22 the moment the piston has reached the end of 120

its down stroke and the port 41 has been uncovered. Now, on the next up stroke of the piston the air thus trapped in the upper end of the cylinder will be forced into the space surrounding the cylinder that is formed by the housing 36 where it is further compressed and from which it escapes into the power cylinder to scavenge the same the moment the air inlet ports 10 and 10 the exhaust ports 14 are uncovered. After the engine has been running for a given length of time the water in the jackets of the power cylinder will become heated to a boiling point, steam will be generated which 15 escapes into the steam pocket at the upper end of the cylinder where it is superheated owing to the greater heat of the casing forming the pocket, and from which it escapes into dome 223 from which it may 20 be led into the upper end of the power cylinder through the high pressure air pipe and utilized as a power medium, the air supply in the meantime having been cut off from the pipes by the valve 83.

25 It will be understood that the above described operation applies to both cylinders of the engine, and where the engine is built with a greater number of cylinders the same operation will prevail for each cylinder of 30 the engine.

It will be noted in the drawings that the cranks of the main shaft 26 are set opposite to each other, and also that the valve operating cams for the two cylinders are 35 set oppositely on the shaft 160 so that the air and fuel cams at the opposite ends of the cylinders will be alternately operated to admit a charge of air or fuel simultaneously in the opposite ends of the two cylinders to 40 thus drive the piston on each power stroke in opposite directions.

In order to provide for a more thorough vaporizing of the oil as it is injected into the upper ends of the power cylinders, I 45 arrange a tubular casing 175 in the spaces between the upper sections 17 and the ends of the pistons, said tubular casings extending from the fuel inlet ports 68 toward the centers of the pistons and having their inner ends terminating in perforated hollow spherical sections 176 through which the vapor passes into the cylinders before being ignited. The outer ends of the tubular sections are spaced a short distance from the 50 walls of the cylinders so as to provide passages for the circulation of the air injected into the cylinders. The upper ends of the pistons and also the lower ends of the steam pockets 20 are recessed as at 177 so that as 55 the vapor passes through the perforations of the sections 175 it will strike against the sides of the recesses and be scattered in all directions in the spaces 18 where it will become instantly ignited and expanded to 60 drive the pistons on their power stroke.

After the engine has been running for a short time the tubular sections will become red hot but as the oil vapor will be injected into the cylinder with such force they will pass out through the perforated end of the sections before having time to ignite and their passage through the sections will serve to heat the gases to insure their ignition the instant they reach the cylinders.

In order that the steam may be admitted automatically to the cylinders in the same way as the air and fuel oil, I provide one of each set of cams for operating the air valve rocker arms controlling the admission of the air to the upper ends of the cylinders upon one side of their contacting faces with lateral extensions 230, which however have their faces set back slightly from the main planes of the cams so that the air valves will be operated at a later point of the cycle of the pistons than would be the case with the admission of the air, thus admitting the steam into the cylinders after the pistons have traveled about 80 degrees of their stroke, and when the pressure in the cylinders has been considerably reduced and reduced below that of the steam. As the steam enters the highly heated gases in the cylinders, its temperature and consequently its expansive force will be increased, thus 90 adding additional power to the stroke of the piston and increasing the efficiency of the engine. In Fig. 36 I show an indicator card of the piston when the engine is operating under fuel oil alone, from which it will be observed that during the power stroke of the pistons there is a general decrease of the pressure in the cylinders; and in Fig. 37 I illustrate a card of the piston when the steam is admitted, from which it will be seen that from the moment the steam is admitted the pressure is not only increased but is maintained (owing to the expansion of the steam by being superheated) for about 95 thirty degrees on the power stroke of the piston and that the pressure on the piston is thus increased to the end of its stroke. The steam thus serves the double purpose of increasing the power of the engine and of reducing the temperature of the power cylinders, since the temperature of the ignited gases is between two thousand five hundred (2500) degrees and three thousand (3000) degrees whereas the temperature of superheated steam is considerably less.

100 During the operation of the engine as above described, air will be compressed in the high compressing cylinders as before stated, for use both for starting the engine and for injecting the fuel oil into the cylinders.

105

110 It will thus be seen that I provide an exceedingly simple self-starting and reversible engine whose operation is controlled by a single lever and which is so constructed that 115

the various internal operating parts may be readily got at for inspection or removal without necessitating the taking down of the entire engine, as is the case with all other

5 closed base engines now upon the market and which is of vital importance especially when the engines are built for marine uses where the engine space, particularly in regard to height, is necessarily restricted.

10 What I claim is:—

1. In a double-acting internal combustion engine, a power cylinder having centrally disposed air inlet ports and exhaust ports in the wall thereof, a power piston working

15 in the cylinder controlling said ports, an air compressor for supplying scavenging air to the power cylinder operated by the engine and absorbing a part only of its power, a receiver for the scavenging air communicat- 80

20 ing with the power cylinder, a source of high pressure air supply connected to both ends of the power cylinder, valves controlling the inlet of the high pressure air to said cylinder, means to supply fuel oil to both 85

25 ends of the power cylinder, valves controlling the inlet of the fuel oil thereto, mechanism for alternately operating said valves at the opposite ends of the cylinder as specified, and mechanism for adjusting said op- 90

30 erating mechanism into and out of operative position.

2. In a double-acting internal combustion engine, a power cylinder, a piston working therein, an air compressor for supplying 35

scavenging air to said cylinder operated by the engine and absorbing a part only of its power, a receiver into which the scavenging air is forced under pressure and which communicates with the power cylinder, a fuel

40 oil supply connected to both ends of the cylinder, valves controlling the inlet of the fuel oil thereto, a source of high pressure air supply connected to both ends of the cylinder and to said fuel oil controlling valves, valves

45 for controlling the admission of the high pressure air to the cylinders, mechanism for alternately operating the said valves as specified, and mechanism for adjusting said operating mechanism into and out of oper- 100

50 ative position with either set of valves or with all of the valves.

3. In a double-acting internal combustion engine, a power cylinder, a power piston working therein, an air-tight base con- 105

55 stituting a compression chamber upon which said power cylinder is mounted and wherein air is compressed for scavenging the power cylinder, a source of high pressure air supply connected to both ends of

60 the power cylinder, valves controlling the admission of the high pressure air to the cylinder, means to supply fuel oil to both ends of the cylinder, valves controlling the admission of the fuel oil thereto, mechanism

65 for alternately operating said air and said

fuel oil valves at opposite ends of the cylinder as specified, and mechanism for adjusting said operating mechanism into and out of operative position.

4. In a double-acting internal combustion engine, a power cylinder having air inlet and exhaust ports in the wall thereof, a piston working in the cylinder controlling said ports, an air-tight base constituting a compression chamber upon which said cylinder is mounted, an air compression cylinder arranged tandem with said power cylinder for supplying scavenging air to said power cylinder and which communicates with said base, a source of high pressure air supply connected to both ends of the power cylinder, valves controlling the admission of the high pressure air to the said cylinder, means to supply fuel oil to both ends of the power cylinder and valves controlling the admission of the oil thereto, mechanism for alternately operating said valves, and mechanism for adjusting said valve operating mechanism into and out of operative position. 90

5. In an internal combustion engine, a power cylinder having air inlet ports and exhaust ports in the side wall thereof, a power piston operating in said cylinder controlling said ports, a base, a housing connected to said base in an air-tight manner providing a compression chamber in said base, a compression cylinder for supplying scavenging air to the air inlet ports of said power cylinder and which communicates 100 with said engine base, a piston working in said compression cylinder and connected to said power piston, a crank-shaft mounted in the base, a connecting rod connecting said crank-shaft and the piston working in said 105 air compression cylinder, a source of high pressure air supply connected to said power cylinder, a valve controlling the admission of the high pressure air thereto, a fuel oil supply for said power cylinder, a valve controlling the admission of the oil to the cylinder, mechanism for operating either of the said valves to admit high pressure air or fuel oil to the power cylinder, means for adjusting said oil admission valves to vary 110 the amount of fuel admitted to the cylinder, and means to supply high pressure air to said fuel controlling valves to inject the oil into the cylinder against the pressure therein.

6. In a double-acting self-starting internal combustion engine, a power cylinder having inlet ports and exhaust ports in the walls thereof, a power piston working therein controlling said ports, an air-tight base 125 upon which the cylinder is mounted, constituting a compression chamber, a compression cylinder arranged in tandem with said power cylinder and communicating with said base at both ends, a compressing 130

- piston working in said compression cylinder controlling the communication between the base and the upper end of its cylinder, a connecting rod connecting said pistons, an air chamber communicating with said inlet ports of the power cylinder wherein the air from the compression cylinder is compressed and from which it is admitted into the power cylinder on each stroke of the power piston to scavenge the cylinder of the products of combustion resulting from the ignition of the fuel in the cylinder, a source of high pressure air supply connected to both ends of the power cylinder, valves controlling the admission of the air to said cylinder, means to supply fuel oil to both ends of the power cylinder, valves controlling the admission of the oil thereto, mechanism for alternately operating said valves at opposite ends of the cylinder for admitting either air or fuel oil thereto, or air into one end and fuel oil into the opposite end as specified, and means for controlling the operation of the said valves.
- 25 7. In an internal combustion engine, a base, columns extending therefrom, a sectional power cylinder mounted on the upper ends of said columns and supported above said base, said cylinder having inlet and exhaust ports in the wall thereof, a power piston working in said cylinder controlling said ports, a compression cylinder arranged tandem with the power cylinder, a piston working therein and connected to said power piston, a sectional housing mounted on said columns providing a compression chamber in the base and with which the said compression cylinder communicates, the sections of the housing being connected together and to said base air-tight, a crank-shaft mounted in the base, a connecting rod connecting said shaft with the piston working in said compression chamber, an air receiving chamber communicating with the inlet ports of the power cylinder into which the air from the compression cylinder is conducted and from which it escapes into the power cylinder when said ports are uncovered, means to supply air under pressure to opposite ends of the power cylinder for use as a power medium, valves controlling the admission of the air into said cylinder, means to supply fuel oil to opposite ends of said power cylinder, valves controlling the admission of the oil thereto, and a common mechanism for controlling the operation of the valves as specified.
8. In a double-acting self-starting internal combustion engine, a power cylinder having centrally arranged air inlet and exhaust ports in the wall thereof, a piston working in said cylinder controlling said ports, an air receiving chamber communicating with said air inlet ports, a base, supporting columns for the cylinder extending from said base, a sectional housing slidably held upon
- said columns and connected air-tight to the base providing a compression chamber in the base, an air compression cylinder arranged tandem with the power cylinder and in open communication at its lower end with the compression chamber of the base, the upper end of the said cylinder being in communication with said air receiving chamber, a passage connecting the base with the upper end of said compression cylinder, a compressing piston operating in said compression cylinder controlling the inlet from the base, a source of high pressure air supply connected to both ends of the power cylinder, valves controlling the admission of the air to the cylinder, means to supply fuel oil to both ends of the power cylinder, valves controlling the admission of the fuel oil to the cylinder, a shaft mounted on the engine, cams carried by said shaft for operating said valves, and means for effecting a rotary movement of the shaft to adjust said cams to cause the operation of said valves to admit either air or fuel oil to said power cylinder.
9. In a double-acting self-starting internal combustion engine, a power cylinder having air inlet ports and exhaust ports in the wall thereof, a piston operating in said cylinder controlling said ports, an air receiver into which said inlet ports open, a compressor operated by the engine for supplying scavenging air to the air receiver, a high compression air compressor also operated by the engine, a receiver for the highly compressed air which is piped to both ends of the power cylinder, valves for controlling the admission of the air from said highly compressed air receiver to the power cylinder, means to supply fuel oil to both ends of the power cylinder, valves controlling the admission of the oil thereto, means to supply high pressure air to the fuel controlling valves to force the fuel into the cylinder when said valves are open, mechanism for alternately operating said valves to alternately admit air or fuel oil to the opposite ends of the power cylinder in the sequence specified, and mechanism for controlling the operative positions of the said operating mechanism.
10. In a double-acting self-starting internal combustion engine, a power cylinder having air inlet ports and exhaust ports in the wall thereof, a power piston working in said cylinder controlling said ports, a power shaft to which the piston is connected, a compressor operated by the engine for supplying scavenging air to said power cylinder, a high compression air compressor operated by the engine, a receiver connected to the last named compressor, means connecting the receiver with both ends of the power cylinder for conducting the highly compressed air to said cylinder wherein it is used as a power medium, valves controlling the ad-

mission of the air from the high compression air receiver to the cylinder, means to supply fuel oil to both ends of the power cylinder, valves controlling the admission of the fuel oil thereto, an adjustable shaft operatively connected with the power shaft of the engine, cams carried by said adjustable shaft for alternately operating said valves to alternately admit the air or fuel oil into the power cylinder in the sequence specified, and means for controlling the operative positions of said cams.

11. In a double-acting self-starting internal combustion engine, a power cylinder having air inlet ports and exhaust ports arranged in the wall thereof, a power piston working in the cylinder controlling said ports, a power shaft to which the piston is connected, a compressor operated by the engine for supplying scavenging air to the power cylinder, a source of high pressure air supply connected to both ends of the power cylinder, valves to control the admission of the high pressure air to the cylinder, means to supply fuel oil to both ends of the cylinder, valves controlling the admission of the fuel oil to the cylinder, a reciprocating shaft rotatably mounted on the engine, cams carried by said reciprocating shaft for operating said valves, said cams being so arranged whereby said valves are alternately operated to admit the air and fuel into opposite ends of the power cylinder in the sequence specified as the shaft is reciprocated, and means for rotating said shaft to adjust said cams for operating either the air admission valves or the fuel oil admission valves or one air admission valve and one fuel oil admission valve to alternately admit air and fuel oil into opposite ends of the power cylinder.

12. In a double-acting self-starting internal combustion engine, a water jacketed power cylinder, a power piston working therein, an air compressor operated by the engine for supplying scavenging air to the said cylinder, a high compression air compressor also operated by the engine, a receiver for the highly compressed air, means for conducting the highly compressed air to both ends of the power cylinder, valves controlling the admission of the air to said cylinder, means to supply fuel oil to both ends of the cylinder, valves controlling the admission of the fuel oil to the cylinder, a reciprocating shaft rotatably mounted on the engine, cams carried by said shaft for operating said valves to alternately admit air and fuel oil to the opposite ends of the cylinder as specified, means to supply steam to the said cylinder, means for reciprocating said shaft, and means for rotating the shaft to control the positions of said cams to operate upon said valves to admit the several power mediums to said cylinder.

13. In a double-acting self-starting internal combustion engine, a power cylinder having scavenging air inlet ports and exhaust ports in the wall thereof, a power piston working in said cylinder controlling said ports, said cylinder having an air passage and a fuel passage leading into each end thereof, means to supply high pressure air to said air passages, valves controlling the admission of the air to the cylinder, means to supply fuel oil to said fuel passages, valves controlling the admission of the fuel oil to the cylinder, rocker arms operatively engaging said valves, a reciprocating shaft rotatably mounted on the engine, cams carried by said shaft for engagement with said rocker arms, means for reciprocating said shaft, and means to rotate the shaft to adjust said cams into and out of operative position with the said rocker arms as specified.

14. In a double-acting self-starting internal combustion engine, a power cylinder having centrally arranged scavenging air inlet ports and exhaust ports in the wall thereof, a power piston working in said cylinder controlling said ports, an air passage and a fuel oil passage leading into each end of the cylinder, valves controlling the admission of the air and the fuel oil into the cylinder through said passages, means to supply high pressure air to all of said valves, means to supply fuel oil to the valves controlling the admission of the oil to the cylinder, rocker arms operatively engaging said valves, a reciprocating shaft rotatably mounted on the engine, means for reciprocating said shaft, cams carried by the shaft for engagement with said arms as and for the purpose specified, adjustable tripping devices interposed in the fuel valve operating mechanism, and mechanism for adjusting said shaft longitudinally whereby to regulate the time of operation of said valves with respect to the stroke of the power piston.

15. In a double-acting self-starting internal combustion engine, a power cylinder, a power piston working therein, an air passage and a fuel oil passage leading into each end of the cylinder, a valve controlling each passage, a source of high pressure air supply piped to each valve, a pump for supplying fuel oil to the said valves controlling said fuel passages, rocker arms operatively engaging said valves, a reciprocating shaft rotatably mounted on the engine, cams carried by said shaft for rocking said arms as specified, tripping mechanisms for the fuel valve operating rocker arms, means to rotate said reciprocating shaft to adjust said cams into and out of operation with said rocker arms whereby either said air controlling valves or said fuel valves are alternately operated at opposite ends of the cylinder, means to cut off the supply of air to

- 5 said air valves, and means to cut off the supply of fuel to said fuel valves, for the purposes specified, and means to supply steam to said air valve controlling the air passage at the upper end of the cylinder when the air supply to said valves is cut-off.
- 10 16. In an internal combustion engine, a power cylinder, a power piston working therein, a power shaft connected to said piston, air passages and fuel oil passages arranged in the ends of the cylinder, valves controlling said passages, means to supply high pressure air to said valves, a pump for supplying fuel oil to each of said valves controlling said fuel passages, means to supply fuel oil to said pumps, means for conveying high pressure steam to the valve controlling the air passage at one end of the cylinder, means to cut off the supply of high pressure air to said valve when the steam pressure is on, rocker arms operatively connected to said valves, a reciprocating shaft rotatably mounted on the engine, cams carried by said shaft for engaging said arms when said shaft is reciprocated, a controlling lever for rotating said shaft to adjust said cams into and out of operative engagement with said arms as said shaft is reciprocated and for adjusting said cams for engagement with the arms to admit the several power mediums to the power cylinder as specified, and a governor interposed in the pump operating gear for regulating the stroke of said pump pistons.
- 15 17. In an internal combustion engine, a power cylinder, a power piston working therein, a power shaft connected to said piston, air passages and fuel oil passages arranged in the opposite ends of the power cylinder, valves controlling said passages, means to supply high pressure air to said valves, means to supply fuel oil to the valves controlling said fuel passages, rocker arms operatively connected to said valves, a reciprocating shaft rotatably mounted on the engine, cams carried by said shaft for engaging said arms when the shaft is reciprocated, a controlling lever for rotating said shaft to adjust said cams into and out of operative engagement with the said arms, and means for cutting off the supply of fuel oil to either or both ends of the cylinder when it is desired to admit only air thereto.
- 20 18. In an internal combustion engine, a power cylinder, a power piston working therein, a power shaft to which said piston is connected, an air passage arranged in the end of the cylinder, a valve controlling the inlet to said passage, a source of high pressure air supply piped to said valve, a fuel oil passage also leading into the end of the cylinder, a valve controlling the inlet to said passage, said valve comprising a casing, a valve seat at its inner end having passages leading into said fuel passage of the cylinder.

der, sliding valves arranged in said casing which normally seat against said valve seat and which provide an oil chamber and an air chamber in said casing, means to supply air from said air supply to said air chamber, means to supply fuel oil to said oil chamber, a check valve arranged in said casing to trap the oil supplied thereto, rocker arms operatively engaging said air and fuel oil admission valves, a reciprocating shaft rotatably mounted on the engine, cams carried by said shaft for rocking said arms to open said air and fuel oil admission valves for the purpose specified, and means for rotating said shaft to throw either cam out of operative relation to its respective rocker arm.

25 19. In an internal combustion engine, a power cylinder, a power piston working therein, a power shaft to which said piston is connected, an air passage and a fuel passage arranged in the opposite ends of the cylinder, valves controlling said passages, a source of high pressure air piped to said valves, means to supply fuel oil to the valves controlling said fuel passages, means to supply high pressure steam to said air valves, a reciprocating shaft rotatably mounted on the engine, cams carried by said shaft for operating said valves, means for rotating said shaft to adjust said cams to alternately operate the air valves only at opposite ends of the cylinder, or to alternately operate an air valve at one end of the cylinder and a fuel valve at the opposite end of the cylinder, or for alternately operating said fuel valves and one of said air valves to admit steam to the cylinder, means to cut off the air supply to said air valves when steam is admitted, and means for cutting off the supply of fuel oil to one or both ends of the cylinder so that compressed air only may be used for starting the engine.

30 20. In a double-acting self-starting internal combustion engine, a power cylinder having scavenging air inlet and exhaust ports in its wall, and a recess in the inner side of its head, a power piston working in said cylinder having a substantially funnel-shaped extension at one end providing air passages designed to register with said scavenging air inlet ports when the piston is at the end of its power stroke, said funnel-shaped extension providing a discharge mouth which extends into the cylinder past said exhaust ports and which is designed to snugly fit the said recess in the head of the cylinder when the piston reaches the end of its return stroke whereby to take up the space within the power end of the cylinder and thus permit the compression of the fuel to ignition temperature, an air receiving chamber communicating with said air inlet ports, a base, a compression chamber in the base, an air compression cylinder arranged tandem with the power cylinder and in open

- communication at its lower end with the compression chamber of the base, the upper end of said cylinder being in communication with said air receiving chamber, a passage 5 connecting the compression chamber of the base with the upper end of said compression cylinder, a compressing piston operating in said compression cylinder controlling the inlet from the compression chamber 10 of the base, a source of high pressure air supply connected to both ends of the power cylinder, valves controlling the admission of the high pressure air to the power cylinder, means to supply fuel oil to both 15 ends of the power cylinder, valves controlling the admission of the fuel oil to the power cylinder, a reciprocating shaft mounted on the engine, cams carried by the shaft for operating said fuel oil and air admission 20 valves, and means for effecting a rotary movement of the shaft to adjust said cams to cause the operation of said valves to admit either air or fuel oil to said power cylinder.
- 25 21. In an internal combustion engine provided with air inlet and fuel inlet valves, the combination with a reciprocating shaft having a plurality of cams each being out of longitudinal alignment with respect to its 30 adjacent cams, for the purpose specified, rocker arms operatively associated with said valves and arranged for engagement by said cams to open said valves, and means to manually rotate said reciprocating shaft to 35 successively adjust said cams into and out of operative position with respect to their coacting rocker arms.
22. In an internal combustion engine, comprising a plurality of cylinders each having a fuel inlet leading into the combustion chamber thereof, and a valve controlling each inlet, the combination with a reciprocating shaft geared to the crank shaft of the engine and rotatively mounted on the 45 engine, a rocker arm operatively associated with each valve, cams carried by said reciprocating shaft adapted for engagement with said rocker arms, said cams being arranged out of longitudinal alignment whereby, 50 when the shaft is rotated, to cause their contacting faces to be successively adjusted into and out of position to be engaged by said rocker arms when the shaft is reciprocated, and manually operated means to rotate said shaft.
23. In an internal combustion engine, comprising a plurality of lower cylinders each having an air inlet and a fuel inlet leading into the combustion chambers thereof, and valves for controlling said inlets, the combination with a reciprocating shaft 60 geared to the crank-shaft of the engine and rotatively mounted on the engine, a rocker arm operatively associated with each valve, cams carried by said reciprocating shaft 65 adapted for engagement with said rocker arms, said cams being arranged out of longitudinal alignment throughout the length of said shaft whereby, when the shaft is rotated, to cause the cams to be successively moved into and out of operative position with respect to their coacting rocker arms in the sequence specified, and means to rotate said shaft.
24. An internal combustion engine, comprising a power cylinder, a piston working therein, a crank-shaft connected to the piston, air and fuel injection valves connected to the head of the cylinder, a reciprocating cam-shaft geared to said crank-shaft so that 75 its maximum speed of reciprocation is coincident with the minimum speed of the piston when the main crank is at or near its dead center, means operatively connected to said valves, cams carried by said reciprocating 80 shaft adapted to engage said valve operating means to successively operate the air and fuel injection valves, as specified.
25. An internal combustion engine, comprising a power cylinder, a piston working 90 therein, a crank-shaft connected to the piston, air and fuel injection valves connected to the head of the cylinder, a reciprocating cam-shaft geared to the crank-shaft so that 95 its maximum speed of reciprocation is coincident with the minimum speed of the piston when the main crank is at or near its dead center, means operatively connected to said valves, and cams having their operative faces on their sides carried by said reciprocating cam-shaft adapted to engage said valve operating means to successively operate the air and fuel injection valves, as specified.

In testimony whereof I have hereunto set my hand this 22nd day of April, A. D. 1912.

SIMON LAKE.

C. E. ADAMS.

Corrections in Letters Patent No. 1,096,730.

It is hereby certified that in Letters Patent No. 1,096,730, granted May 12, 1914, upon the application of Simon Lake, of Milford, Connecticut, for an improvement in "Internal-Combustion Engines," errors appear in the printed specification requiring correction as follows: Page 3, line 104, for the word "forced" read formed; page 5, line 96, for the word "pjassage" read *passage*; page 10, line 55, for the reference-numeral "73" read 73; page 16, line 97, for the word "on" read *or*; and that the said Letters Patent should be read with these corrections therein that the same may conform to the record of the case in the Patent Office.

Signed and sealed this 2nd day of June, A. D., 1914.

(SEAL.)

J. T. NEWTON,
Acting Commissioner of Patents.
